Primary Examiner — Leanne Was-Englehart(74) *Attorney, Agent, or Firm* — Temmerman Law Office;
Mathew J. Temmerman(57) **CLAIM**

I claim the ornamental design for a charcoal starter platform, as shown and described.

DESCRIPTION

FIG. 1 is a perspective view as seen from the upper right of a charcoal starter platform, showing my new design;
 FIG. 2 is a front side view thereof;
 FIG. 3 is a back side view thereof;
 FIG. 4 is a left side view thereof;
 FIG. 5 is a right side view thereof;
 FIG. 6 is a plan view thereof; and,
 FIG. 7 is a bottom view thereof.
